UNITED STATES PATENT OFFICE.

CLEMMA R. RANEY, OF CHICAGO, ILLINOIS.

PHONOGRAPH.

1,302,217.

Specification of Letters Patent. Patented Apr. 29, 1919.

Application filed March 31, 1916. Serial No. 88,034.

To all whom it may concern:

Be it known that I, CLEMMA R. RANEY, a citizen of the United States, residing at Chicago, in the county of Cook and State of Illinois, have invented certain new and useful Improvements in Phonographs, of which the following is a full, clear, and exact specification.

My invention relates to phonographs.

10 It has among its objects to provide an improved phonograph.

It also has among its objects to provide improved means whereby a series of records may be reproduced in a predetermined succession continuously and automatically. A further object of my invention is to provide improved means whereby a series of records arranged in predetermined order may be successively supplied to the record rotating mechanism of the machine and improved means whereby they may be discharged therefrom after they have been reproduced. A still further object of my invention is to provide improved means for controlling the sound arm and needle of the reproducing mechanism in such a manner as automatically to place the same in starting position upon a record, and improved mechanism whereby the sound arm may be automatically returned to its initial position after the completion of the record. More specifically, my invention has among its objects to provide improved and coöperating mechanism whereby the several results mentioned above

35 may be obtained in the desired sequence, and to produce a machine adapted to reproduce a predetermined series of records automatically and continuously, which will function with certainty and accuracy during a protracted period of service without the necessity for repairs, which is capable of use even in the hands of an unskilled operator without danger of breakage, and which may at the same time be manufactured at small expense. These and other objects of my invention will, however, hereinafter more fully appear.

In order that my invention may be fully and clearly disclosed, I have shown for purposes of illustration in the accompanying drawings one embodiment which the same may assume in practice, illustrating the same as applied to a machine of a standard type employing disk records.

In these drawings,—

55 Figure 1 is a partial plan view of this machine equipped with my improvement, a portion of the record table being broken away to facilitate illustration.

Fig. 2 is a side elevation of the mechanism shown in Fig. 1, a plurality of records being shown in the machine and portions of the frame-work of the latter being broken away to facilitate illustration.

Fig. 3 is a side elevation of a portion of the mechanism, the record carrying support being shown in elevated position ready to receive the records.

Fig. 4 is a detail sectional view of the record support showing the same in normal position and ready to discharge one of a plurality of records thereon.

Fig. 5 is a detail side elevation of a portion of the record support.

Fig. 6 is a detail transverse sectional view of the record table and its counter-balancing and rotating mechanism.

Fig. 7 is a partial plan view of one form of record showing the different series of grooves and the axial rings thereon.

Fig. 8 is a detail view showing the sound arm in inoperative position with respect to a record.

When broadly considered, this illustrative construction includes means whereby a series of records carried on a suitable record support may be fed successively and in a predetermined order to a rotating record table, means whereby when a record has been supplied to the table the sound arm and needle may be automatically placed in starting position upon the record, means whereby when the record has been reproduced the sound arm may be returned to its inoperative position, means whereby the record table may be operated to discharge the record therefrom into a suitable receptacle, means whereby the record table may be returned automatically to operative position, and means whereby another record may be fed thereto, the sequence of operation above outlined being continued until all of the records have been reproduced.

In this illustrative construction, I have shown a machine provided with a suitable base 52 having a normally horizontally disposed record carrying table 31 rotatably mounted thereon and connected through op-

erative connections hereinafter described to an upstanding motor driven shaft 34 which may be connected to any suitable motor (not shown) carried in the machine casing. Pivotally mounted on this base is also a reproducer arm 1 adapted to move to and fro laterally across the face of a record carried on the table 31 and carrying a sound box 39 of any standard form adapted to engage the playing surface of a record on the table 31, this sound box being shown for purposes of illustration herein as being equipped with a needle. Disposed on opposite sides of this record table 31 are suitable supports 2 and 54. As shown, these supports extend a substantial distance above the table and one of them is pivotally connected at its upper end to a swinging cross arm 3 having a suitable foot-piece adapted when the cross arm is in normal position to be received in a corresponding notch formed in the upper end of the support 54. Carried upon this arm 3 and movable therewith, is the mechanism for supporting the series of records to be played, and feeding the same successively to the rotating table 31, the records ordinarily being placed upon the support when the cross arm 3 is in the elevated position shown in Fig. 3, and then lowered into coaxial relation with respect to the rotating table 31 by swinging the cross arm 3 about its pivot to the position shown in Fig. 2.

This record supporting and feeding mechanism is shown in detail in Figs. 4 and 5. As illustrated in these figures, it will be noted that a record supporting and guiding member 30 is preferably fixed to the member 3 and disposed at right angles thereto in such a manner as to be readily accessible when the member 3 is raised, and be disposed in vertical position directly over the axis of the table 31 and axially of a record thereon when the arm 3 is lowered. This record supporting and guiding member is, as shown, preferably slotted longitudinally at a point intermediate its ends to receive a plate 45' reciprocable longitudinally thereof, and carrying a plurality of oppositely disposed lugged members 45 and 46, the lugs on which are adapted successively to engage with teeth on the opposite sides of a gear wheel 47 journaled in the slotted portion of the support, the member 45 itself also being suitably slotted longitudinally to permit the reciprocation thereof relative to the support and the gear wheel. As shown, the member 45' is also provided with a lower plunger portion 41 fixed thereto and extending through the end of the support 30 to a point adjacent the table 31. Obviously, by reciprocation of this plunger in one direction, the lugged member 46 is disengaged from its tooth on the gear 47 and the lugged member 45 brought into engagement with a tooth on said gear 47, and when the plunger

41 is moved in the opposite direction by the weight of the records, the lugged member 46 is brought into engagement with the gear 47 and the other lugged member 45 disengaged therefrom. Carried upon this support 30 is a series of records 48 each having an axial perforation therein provided with a transversely recessed portion preferably having its sides sloping toward the plane of the record. In the form of my invention shown herein, it will be noted that each record carries on its upper and lower face an axially disposed ring 44, the inner edges of which are each beveled toward the plane of the record and so spaced apart that when one record is laid upon another the teeth on the gear 47 may enter the interval between the rings and co-act with the beveled edges thereof in successively discharging records from the support 30. As shown in Fig. 7, I have also provided a notch 62 in each of these rings so that the records may be readily slipped onto the support and pass over the gear 47 and be retained on the support by a simple turning movement of the record sufficient to carry the notch 62 out of registry with the gear.

The operation of this record feeding mechanism will be clear from a consideration of Fig. 4, wherein it will be noted that with the plunger 41 in its lowermost position the lugged member 46 engages with one of the upper teeth of the gear 47 while the lugged member 45 is free from engagement with the teeth on the lower side of that gear. Thus, it will be noted that the gear is held against rotation and that the series of records is supported on the support 30 due to the engagement of the beveled edge of the upper ring 44 on the bottom record 105 with one of the inclined faces of a tooth on the gear 47. When, however, the plunger 41 is reciprocated, it will be noted that the lugged member 46 is moved upward in such a manner as to release the gear 47. As a result, due to the weight of the records the gear 47 is rotated, causing the tooth which has supported the bottom record 48 to be turned out of the way of the same and to the left to free that record, which then slides down on the lower end of the support 30 to the table 31. Moreover, after the gear 47 has moved through only the space of one tooth, it will be noted that the moving tooth thereon then engages the lugged member 45 115 in such a manner as to limit the rotation of the gear, and that when the plunger 41 is released, due to its own weight the member 45 is lowered to return the lugged member 46 into engagement with the next upper tooth on the gear 47. Thus, it will be noted that as a result of this sequence of operation a single record will be discharged and the parts automatically returned to their normal positions ready to release an- 130

other record when the plunger 41 is again lifted.

While my improved mechanism for feeding a plurality of records successively to the 5 reproducing mechanism is not limited to use in connection with such a device, I have here shown the same for purposes of illustration as applied to use in connection with a tilting rotating record table which is adapted 10 to tilt to discharge a record therefrom after the same has been reproduced, and in its tilting movement actuate the axially disposed record feeding plunger 41 and its co-operating mechanism in such a manner as 15 to cause another record to be supplied to the table by the time the latter has returned to its normal horizontal position. As shown, this table 31 is suitably rotatably mounted, as on ball bearings, on a suitable 20 support 24 which is in turn fixed to a rearwardly located transverse rock shaft 25 itself journaled in suitable pin bearings 4 carried on suitable upstanding supports on the base 52. Preferably, though not necessarily, 25 this record table 31 is also provided with a laterally extending arm 37 fixed thereto and extending through a suitable opening in a co-operating upstanding arm 36 connected through a suitable pivotal connection 35 to 30 the upstanding rotating power shaft 34, the connection and arrangement of the arms 37 and 36 being such that the arm 37 may move relative to the arm 36 and thus enable that arm to continue to rotate the table 31 even 35 during the tilting of the same to discharge a record therefrom. As shown, this tilting movement is a forward tilting movement and is obtained through suitable counter-balancing mechanism connected to the member 24, the latter preferably being provided 40 with a rearwardly extending arm 23 carrying thereon an adjustable weight 22, which is so located and of such weight that it is adapted normally to hold the table 31 in 45 horizontal position when empty and, due to the weight of the record and the location of the same with respect to the axis of the shaft 25, to be overbalanced by the weight of a record on the table 31 and thus permit 50 the record table to tilt forward to discharge the record therefrom. Thus, it will be noted that the weight of the record itself causes its own automatic discharge from the table 31 whenever the weight 22 is free to move 55 upward, and that, as soon as the record has been discharged from the table, the latter, due to the action of the weight 22, will be immediately returned to its normal horizontal position ready to receive another 60 record. It will also be noted that as the table 31 tilts downward, it also acts upon the plunger 41 in such a manner as to reciprocate the lugged members 45 and 46 and cause another record to be fed down from 65 the support 30 into position thereon as soon

as it has returned to its normal position. Attention is also directed to the fact that due to the provision of the continuously operative driving connection 36, 37, the table when so returned to its normal position is 70 rotating so that it may thus immediately begin to perform its rotating function during the reproduction of the new record. It will be evident, however, that both the feeding and tilting mechanism may be used, if desired, without this continuous rotation. 75

Co-operating with my improved automatically operating table tilting and returning mechanism just described, I have provided improved means acting to prevent the tilting of the table 31 during the reproduction of a record carried thereon. As shown, these means assume the form of mechanism normally adapted to hold the weight 22 against movement during the playing of a record, 80 and are connected to the sound arm 1 and so controlled by the movement thereof that when this arm has moved over the record in the usual manner to complete the reproduction thereof, the weight 22 is automatically released. As shown, the arm 1 carries at its rear end a suitable vertically disposed pivot member 5 pivotally mounted in suitable supports 58 and 59, preferably formed on the member 2. Carried on this post or 85 pivot member 5 is a suitable laterally extending arm 16 which, when the sound arm 1 has completed its travel over a record on the table 31, is adapted to engage an upstanding latch member 19 pivoted on the support 90 52 and swing the same backward out of engagement with a co-operating latch member 18 mounted on a bracket 15 and projecting rearwardly from the rock shaft 25, and thus release that shaft and the weight 22 95 fixed thereto so that the weight of the record on the table 31 may then raise the weight 22 and cause the table 31 to tilt to discharge the record therefrom. As shown, the latch member 19 is normally held in elevated position ready to engage the co-operating latch member 18 by means of a spring 21, and thus it will be noted that when the table 31 has discharged its record and is returned empty to its normal position, the latch 19 is 100 in position to engage its co-operating latch member 18 again to hold the table in its playing position until the completion of the reproduction of the new record. 105

Co-operating with this mechanism for releasing the tilting mechanism for the table 31, I have also provided improved mechanism adapted automatically to carry the member 16 out of the path of the latch member 19 and thus permit the latch members 18 and 19 to engage; this mechanism preferably being also adapted, after the reproduction of a record, to return the sound arm to its starting position shown in Fig. 1. This mechanism, as shown herein, is con- 110 115 120 125 130

nected to the tilting mechanism above de-
scribed and is shown to include a lug 17
carried on the sound arm 1 and adapted,
when the reproduction of a record has been
completed, to engage an adjustable set-
screw 8 carried on a rearwardly extending
arm 9 pivotally connected to a forwardly
and upwardly extending portion of an arm
11 fixed by suitable means 10 to the rock
10 shaft 25. Thus, it will be noted that, as the
reproducing mechanism moves over the rec-
ord on the rotating table 31, the member 17
is brought into juxtaposition to the mem-
ber 8 so that after the latch releasing mech-
anism 16, 18, 19 is actuated, and as a result
15 of the tilting of the table 31, the member 8
will be brought into engagement with the
member 17 and thereby swing the sound
arm 1 in the opposite direction about its
pivot 5 to its inoperative position. In so
20 doing, it will be noted that since the mem-
ber 16 is connected to the arm 1 that mem-
ber is swung out of the path of the latch
19, thereby enabling the latter to engage
25 with the member 18 when the table 31 is
returned to its normal horizontal position.

Coöperating with the mechanisms above
described and likewise controlled by the
tilting movement of the table 31, is im-
30 proved mechanism for applying the repro-
ducing mechanism or sound box 39 to the
new record. As shown herein, this mech-
anism includes automatically acting means
35 for elevating the sound arm 1 from its in-
operative position and lowering the same
upon the new record which has been auto-
matically placed upon the rotating table 31
as the latter is returned to its normal pos-
40 ition. This mechanism, as shown, is carried
upon a suitable horizontal portion formed
on the rock arm 11 and includes a suitable
bracket or frame 55 pivotally connected to
that arm in such a manner as to rock about
45 the same as an axis, this bracket being nor-
mally held in a predetermined position by
means of a weight 14 carried on a depend-
ing arm 56. In the form of my invention
shown, it will also be noted that this bracket
50 carries a spiral gear 12 adapted to mesh
with a second spiral gear 43 suitably jour-
naled on the bracket and having rotatably
connected thereto a wheel 13 preferably hav-
ing a rubber tire and adapted to engage the
55 periphery of the rotating record table 31
and be rotated thereby. As shown, a sec-
ond wheel 38, also preferably provided with
a rubber tire, is fixed to and rotatable with
the spiral gear 12, this wheel being adapted
60 when slowly rotated through the rotation
of the wheel 13 and the spiral gears, to lift
the sound arm 1 from its support 52 and
lower the same upon the record, through
the medium of certain coöperating elements
65 carried on the sound arm. These elements,

obviously, may assume various forms. Here-
in, however, it will be noted that a spring
32 is disposed longitudinally of the sound
arm and beneath the same and at one side
of a longer, laterally extending and inclined
lug 33, likewise carried by the arm, in such
a position that when the rotating table 31
has returned to its normal position and the
sound arm is in its inoperative position
shown in Fig. 3, this spring will press down
upon the periphery of the slowly rotating
70 wheel 38. As a result, the arm 1 will be
moved laterally to the right from the posi-
tion shown in Fig. 3 in such a manner as
shortly thereafter to bring the lower end
75 of the longer, laterally extending lug 33 into
engagement with the periphery of the
wheel, and as the latter continues to rotate,
cause this lug to be fed across the periphery
80 of the wheel in such a manner as to result
in a slow and gentle raising movement of
the arm followed by a slow and gentle
lowering movement of the same sufficient
85 to bring the needle carried by the sound box
39 into proper starting position upon the
edge of the new record carried on the then
90 rotating table 31. Thus, it will be noted
that after the table 31 has been returned
to normal position, the rotation of the same
is utilized to elevate the sound arm 1 auto-
matically and in the same fashion lower
95 the arm in a delicate and accurate manner
in its starting position upon the edge of
the new record which has been automatic-
ally placed upon the table as the latter is
returned to position. It will also be noted
100 that through the connection of the arm 11
to the rock shaft 25 and the engagement of
the wheel 13 with the rotating table 31, the
needle placing mechanism is controlled by
105 this table, the same being automatically
tilted thereby out of the path of the re-
turning sound arm and automatically re-
turned to normal position and set in oper-
ation by the table when the latter is re-
turned to its record receiving position.

Coöperating with the mechanism just de-
scribed, it will be noted that I have provided
improved means whereby the sound arm 1
may have a limited vertical movement with
respect to its pivot in order that the same
115 may be lifted as above described prior to the
lowering of the same upon the record, and
that the same may rise and fall during the
travel of the same over a record. As shown,
these means include a suitable slot formed in
120 the support 58 for the pivot pin 5 and so
disposed that this pin 5 may have a limited
rocking movement about its lower support
59. Obviously, due to the provision of this
mounting for the pin 5, the arm 1 is not
125 only free to have a limited vertical move-
ment enabling the same to be lifted prior to
being placed in starting position, but is

also free to move vertically while the needle on the sound box 39 is traversing the record, the mounting being such that the arm may accommodate itself to any irregularities in the surface of the record and thereby improve the quality of the reproduction. In this connection, attention should also be directed to the fact that through the provision of a spring 6 secured at one end to the member 8 and attached at the other end to the arm 1 through any suitable adjustable connection 7, a portion of the weight of the arm is taken off of the needle and the same effectually counter-balanced in such a manner as to assist materially in the proper functioning of the reproducing mechanism.

While any desired receptacle may be used to receive the records discharged from the tilting table 31, it is highly desirable for some means to be provided whereby as the successive records are discharged the same are protected from injury. I have accordingly illustrated such a means in Figs. 1 and 2, wherein it will be noted that an inclined chute or guideway 27 is provided formed of strips projecting forwardly from the machine and adapted to underlie the edges of the discharged record and conduct the same downward into a receptacle comprising a circular piece 29 extending above and below the guides. Thus, when a record slides down the guides 27 it is retained within the chute formed by the latter and brought up against the member 29 in such a manner as to arrest its downward movement and cause it to drop flat upon the bottom of the receptacle without injury either to itself or to any other records therein, the rings 44 also coöperating in preventing the injury of the playing surfaces. As shown, a narrow strip 28 is preferably also secured to the lower edge of the member 29 and adapted to underlie the records in the receptacle thus formed, and this strip is connected to a suitable part of the support or base by means of a brace 42. Here, attention should also be directed to the fact that I have herein shown means whereby as a rotating record is discharged from the rotating table 31 it is deflected onto the guides 27. As shown, these means include an upstanding member 26 disposed at one side of the machine and leading to one of the side walls of the chute. Obviously, as the rotating record is discharged, it will engage this member and, due to its own rotation, during its discharging movement travel along the same and the adjacent edge of the chute in such a manner as to be guided definitely until it passes out of the guides 27, whereupon as hereinabove brought out, it will engage the member 29 and drop flat into the receptacle.

Having now described the several component mechanisms, next let us consider the operation of the complete mechanism. With the parts in the position shown in full lines in Fig. 1, when it is desired to set the machine in operation, the member 3 is raised as shown in Fig. 3 and one or more of the records is preferably placed upon the record support 30 while the latter is in elevated position as shown in that figure. For purposes herein, we will assume that a series of records is so placed thereon. This support, with the records thereon, is then lowered into operative position with respect to the table 31, i. e. to the position shown in Fig. 2 wherein the plunger 41 first engages the table 31. With the parts in this position, when it is desired to begin the use of the records upon the support, the bottom record may be dropped into operative position upon the table and the machine started by manual operation of the plunger 41 and a manual placing of the needle in starting position. However, in a preferred method of operation, the operator simply releases the latch 19 and thereby sets the automatic mechanism in operation to tilt the then empty table 31 and thus actuate the feeding plunger 41 to cause a record to be supplied to the table as it returns to its normal position, the record being guided in its delivery movement by the member 30 and held in centered position by the plunger 41. Obviously, as the table returns to normal position, the rotation of the same will also cause the wheel 13 to be rotated and, through the train of mechanism connected thereto, thereby cause the sound arm 1 to be raised and lowered in proper starting position upon the record. When the record has been reproduced, the latch 19 will be automatically tripped by the member 16 and the tilting table released in such a manner as to enable it to discharge the record therefrom and at the same time tilt the arm 11 and the reproducer applying mechanism thereon out of the path of the sound arm as the latter is swung back to its inoperative position by means of the engagement of the lug 8 with the connection of the same to the sound arm. As above described, when the table 31 has been returned to normal position, a second record will then be fed down thereon through the action of the plunger 41 and the gear 37, and since the arm 11 and the reproducer applying mechanism thereon has returned to normal position with the table, as soon as the record has been placed on the table, through the action of the wheel 13 and its coöperating mechanism the sound arm will be raised and lowered to start the reproduction of the new record. When this record has been played, the sound arm 1 will of course then actuate the

tripping mechanism automatically in such a manner as to cause the mechanism to operate automatically in the manner above described. Obviously, this operation will be 5 continued automatically so long as there are records on the record support 30.

It will be noted that in the operation of this illustrative construction the entire mechanism is automatic, the several co-operating mechanisms being set in operation 10 by one another in the desired sequence as a result of the automatic action of the mechanism following the tripping of the latch when the machine is started, or the automatic 15 action of the sound arm as it moves relative to its work. It will also be noted that this operation occurs not only automatically but with decided rapidity, so that there need not necessarily be long intervals 20 between the reproduction of the successive records. Moreover, in order further to decrease the interval between the reproduction of the successive records, it will be noted that I have provided the records 48 25 with a coarse, non-playing spiral groove near their centers, adapted to bring the reproducer arm more rapidly into position to operate the record changing mechanism after the record has been reproduced, this 30 coarser groove being shown at 49 in Fig. 7. By the provision of this groove 49 and the co-operating stylus and trip mechanism, it will also be observed that means are provided whereby, despite any variation in the 35 length of the playing grooves on the record, the stylus is always carried through a definite predetermined path on the record, so that the controlling mechanism actuated thereby may remain in a fixed position, 40 thereby eliminating all difficulty with adjusting the controlling mechanism for records of different length. In connection with the operation of the mechanism shown, it will also be noted that it is unnecessary to 45 provide any drive other than that which rotates the record table, the several mechanisms being so constructed and arranged that they function automatically as a result 50 of gravity and the transmission of this rotary movement thereto. Attention is also particularly directed to the sound arm placing mechanism, which it will be observed makes it possible to place the needle upon the record with great accuracy and with the 55 same degree of delicacy obtainable by even the most careful operator, the movement in fact closely approximating the movement of the same when manually applied by such an operator. These and other advantages 60 of my improvement will, however, be clearly apparent to those skilled in the art.

While I have in this application specifically described one embodiment which my invention may assume in practice, it is to

be understood that in accordance with the 65 patent laws the invention is not limited thereto but may be modified in various other forms without departing from its spirit, and that it is my intention to include all such modifications or embodiments of the 70 same within the scope of the appended claims.

What I claim as new and desire to secure by Letters Patent is:

1. In a phonograph, a record rotating 75 member movable bodily to discharge a record therefrom, and means controlled thereby for supplying a new record thereto.
2. In a phonograph, a record rotating table movable bodily to discharge a record 80 therefrom, and means successively actuated thereby to supply successive records thereto.
3. In a phonograph, a tiltably mounted record rotating table, and means controlled thereby for supplying a new record thereto. 85
4. In a phonograph, a tilttable record rotating table, and means including mechanism intermittently engageable thereby for supplying records thereto.
5. In a phonograph, a tilttable record rotating table, and means actuated by the tilting movement thereof for supplying a record 90 thereto.
6. In a phonograph, a tiltably mounted record rotating table, and means for normally retaining said table in record receiving position. 95
7. In a phonograph, a tiltably mounted record rotating table pivoted at one side of its rotating axis, and counter-balancing 100 means for said table.
8. In a phonograph, a tiltably mounted record rotating table, and co-operating record centering means effective upon a tilting movement of said table to release a record 105 therefrom.
9. In a phonograph, a record rotating table movable to discharge a record therefrom, and co-operating record centering means disposed in operative relation therewith in one 110 position of said table.
10. In a phonograph, a tiltably mounted record rotating table, and record feeding means having an actuating member disposed coaxially with said table. 115
11. In a phonograph, a movable record rotating table, and record feeding mechanism including a coaxially disposed intermittently engaged member normally centering records thereon. 120
12. In a phonograph, a movable record rotating table, and superimposed record feeding mechanism having a guiding member extending substantially to the surface of said table. 125
13. In a phonograph, a movable record rotating table, and superimposed mechanism for delivering records thereto having a guid-

- ing and actuating member disposed coaxially with said table.
14. In a phonograph, record feeding mechanism including an axially disposed normally stationary record supporting and guiding member, and means thereon for successively releasing records therefrom.
15. In a phonograph, record supporting mechanism including an axially disposed normally stationary guiding member, record feeding mechanism thereon, and means for actuating said feeding mechanism.
16. In a phonograph, record supporting mechanism including an axially disposed normally stationary guiding member, record feeding mechanism thereon, and a reciprocable means disposed within said guiding member for actuating said feeding mechanism.
- 20 17. In a phonograph, an axially disposed normally stationary record supporting and guiding member, a rotatable toothed member carried thereon, and cooperating means for intermittently actuating the same to feed 25 a record therefrom.
18. In a phonograph, an axially disposed normally stationary record supporting and guiding member, a rotatable toothed member carried thereon, and cooperating reciprocable controlling means therefor guided in said guiding member.
- 30 19. In a phonograph, an axially disposed normally stationary record supporting and guiding member, records thereon having laterally grooved axial openings therein, and feeding means on said support engageable with the walls of said grooves.
- 40 20. In a phonograph, a frame, a rotating record table thereon, a swinging member disposable over said table, and coaxially disposed normally stationary record supporting and feeding means carried on said swinging member.
- 45 21. In a phonograph, a tilttable record rotating table, and means for rotating the same during a portion of the tilting movement thereof.
- 50 22. In a phonograph, a tilttable record rotating table, and means for continuously rotating the same throughout the tilting movement thereof.
- 55 23. In a phonograph, a tilttable normally operative record rotating table, and means for rotating the same during its to and fro movement.
24. In a phonograph, a tilttable record rotating table, counter-balancing means therefor, and means for rotating said table during its tilting movement.
- 60 25. In a phonograph, a record rotating table tilttable about an axis at one side of its rotating axis, and means normally holding said table in horizontal position tilttable by the weight of a record thereon.
26. In a phonograph, a movable record rotating table, and means for moving said table to discharge a record therefrom after a predetermined rotation of a record carried thereby.
27. In a phonograph, a tilttable record rotating table, reproducing mechanism coöperating with a record thereon, and means for automatically tilting said table after the reproduction of a record thereon.
28. In a phonograph, a tilttable record rotating table, reproducing mechanism coöperating with a record thereon, and means controlled by said reproducing mechanism for automatically tilting said table after the reproduction of a record thereon.
29. In a phonograph, a tilttable record rotating table, swinging reproducing mechanism movable over a record thereon, and coöperating means controlled by said mechanism for tilting said table and swinging said reproducing mechanism toward starting position.
30. In a phonograph, a movable individual record rotating table, swinging reproducing mechanism movable over a record thereon, and coöperating means controlled by said mechanism for moving said table bodily and swinging said reproducing mechanism toward starting position.
31. In a phonograph, a movable individual record rotating table, reproducing mechanism movable over a record thereon, means controlled by said mechanism for moving said table bodily, and means actuated by said table for supplying another record thereto.
32. In a phonograph, a movable record rotating table, reproducing mechanism movable over a record thereon, and means controlled by said reproducing mechanism for moving said table to discharge a record therefrom.
33. In a phonograph, a movable record rotating table, reproducing mechanism movable over a record thereon, and means controlled by said reproducing mechanism for moving said table to discharge a record and returning said table to normal position.
34. In a phonograph, a movable record rotating table, reproducing mechanism movable over a record thereon, means controlled by said reproducing mechanism for moving said table to discharge a record and returning said table to normal position, and automatically acting means for delivering another record to said table.
35. In a phonograph, a movable record rotating table, reproducing mechanism movable over a record thereon, means controlled by said reproducing mechanism for moving said table to discharge a record and returning said table to normal position, and automatically acting means controlled by one of

said elements for delivering another record to said table.

36. In a phonograph, a movable record rotating table, reproducing mechanism movable over a record thereon, means controlled by said reproducing mechanism for moving said table to discharge a record and returning said table to normal position, and automatically acting means controlled by said table for delivering another record to said table.

37. In a phonograph, a record rotating and discharging table, reproducing mechanism movable over a record thereon, means controlled by said table for applying said reproducing mechanism to a record, and means controlled by said reproducing mechanism for substituting records on said table.

38. In a phonograph, a record rotating and discharging table, reproducing mechanism movable over a record thereon, means actuated by said table for applying said reproducing mechanism to a record, and means controlled by said reproducing mechanism for substituting records on said table.

39. In a phonograph, a bodily movable rotating record table, reproducing mechanism movable over a record thereon, means controlled and actuated by said table for applying said reproducing mechanism in starting position upon a record thereon, and means controlled by said reproducing mechanism for substituting records on said table.

40. In a phonograph, a record rotating table, movable reproducing mechanism engageable with a record thereon, means controlled by said reproducing mechanism for substituting a new record thereon, and means engageable with the periphery of said table for controlling said reproducing mechanism.

41. In a phonograph, a movable record rotating table, movable reproducing mechanism engageable with a record thereon, and controlling the movement of said table, and means intermittently engageable with the periphery of said table for adjusting said reproducing mechanism to starting position upon a record thereon.

42. In a phonograph, a movable individual record rotating table, reproducing mechanism movable over a record thereon, and automatically acting mechanism controlled by said reproducing mechanism for discharging a reproduced record, supplying a new record thereto, and applying said reproducing mechanism to the new record.

43. In a phonograph, a movable individual record rotating table, reproducing mechanism movable over a record thereon, and automatically acting mechanism controlled by said reproducing mechanism for actuating said table to discharge a reproduced record, and thereafter supplying a new record thereto, and applying said reproducing mechanism to the new record.

44. In a phonograph, a rotating record table, a counter-balanced support therefor movable about a transverse axis at one side of the rotary axis thereof, and latching mechanism normally holding said table in horizontal position.

45. In a phonograph, a rotating record table, a counter-balanced support therefor movable about a transverse axis at one side of the rotary axis thereof, latching mechanism normally holding said table in horizontal position, reproducing mechanism, and means controlled thereby for releasing said latching mechanism.

46. In a phonograph, a rotating record table, a counter-balanced support therefor movable about a transverse axis at one side of the axis thereof, latching mechanism normally holding said table in horizontal position, movable reproducing mechanism, and co-operating means controlled thereby for releasing said latching mechanism and moving said reproducing mechanism toward inoperative position.

47. In a phonograph, a rotating record table, a counter-balanced support therefor movable about a transverse axis at one side of the axis thereof, mechanism normally holding said table in horizontal position, movable reproducing mechanism, means controlled thereby for releasing said support and rendering said reproducing mechanism inoperative, and means controlled by said table for supplying a new record thereto.

48. In a phonograph, a rotating record table, a counter-balanced support therefor movable about a transverse axis at one side of the axis thereof, mechanism normally holding said table in horizontal position, movable reproducing mechanism, means controlled thereby for releasing said support and rendering said reproducing mechanism inoperative, means controlled by said table for supplying a new record thereto, and means controlled by said table for placing said reproducing mechanism in starting position upon said new record.

49. In a phonograph, a rotary record table, a counter-balanced support therefor movable about a transverse axis at one side of the axis of said table when a record is disposed on said table, and releasable means normally holding said table in horizontal position.

50. In a phonograph, a rotary record table, a counter-balanced support therefor movable about a transverse axis at one side of the axis of said table when a record is disposed on said table, releasable means normally holding said table in horizontal position, and means for rotating said table in any position thereof.

51. In a phonograph, a rotary record table, a counter-balanced support therefor movable about a transverse axis at one side

of the axis of said table when a record is disposed on said table; releasable means normally holding said table in horizontal position, movable reproducing mechanism, and 5 coöperating means controlled thereby for releasing said holding mechanism and moving said reproducing mechanism toward inoperative position.

52. In a phonograph, a rotary record 10 table, a counter-balanced support therefor movable about a transverse axis at one side of the axis of said table when a record is disposed on said table, releasable means normally holding said table in horizontal position, movable reproducing mechanism, co- 15 operating means controlled thereby for releasing said holding mechanism and moving said reproducing mechanism toward inoperative position, means for supplying a new 20 record to said table, and automatically acting means for placing said reproducing mechanism in starting position thereon.

53. In a phonograph, a record rotating 25 table, tilting mechanism therefor whereby the same may be tilted about a transverse axis to discharge a record therefrom, and means for receiving said discharged record.

54. In a phonograph, record discharging 30 mechanism including a tilttable record rotating table, an inclined record chute comprising guiding and supporting means for the record, a receptacle, and means communicating with said chute for arresting the movement of the record and causing the 35 same to drop bodily into the receptacle.

55. In a phonograph, a record rotating 40 table, tilting means for discharging a record therefrom while the same continues to rotate, guiding means engageable by the rotating record as it is discharged, a coöperating chute receiving the same therefrom, and a receptacle receiving the records from 45 said chute.

56. In a phonograph, record discharging 50 mechanism including a tilttable record rotating table, a downwardly inclined record chute comprising guiding and supporting means for the record, a receptacle beneath said chute, and means communicating with 55 said chute for arresting the movement of the record and causing the same to drop bodily into the receptacle.

57. In a phonograph, a record rotating 60 table, tilting means for discharging a record therefrom while the same continues to rotate, lateral guiding means engageable by the rotating record as it is discharged, a downwardly inclined chute receiving the record therefrom, and a lower receptacle receiving the record from said chute.

58. In a phonograph, record rotating 65 means movable to discharge a record therefrom, reproducing mechanism co-acting with a record thereon, record substituting means, and means controlled by said repro-

ducing mechanism and actuated by said rotating means for actuating said substituting means.

59. In a phonograph, disk record rotating 70 means, reproducing mechanism co-acting with a record thereon, record discharging mechanism actuated by gravity, and means controlled by said reproducing mechanism for setting said discharging mechanism in operation.

75

60. In a phonograph, a tilttable record rotating table, automatically acting mechanism for tilting said table to discharge a record therefrom, and automatically acting record feeding mechanism operatively connected with said elements.

80

61. In a phonograph, a record rotating table, means for depositing records thereon, means for tilting said table to discharge a record therefrom, reproducing mechanism, 85 and means controlled thereby for setting said record discharging and depositing means in operation.

62. In a phonograph, a tilttable record rotating table, a plurality of records supported 90 above the same, and means controlled by the tilting movement of said table for releasing the lowermost record from said support and retaining the remainder thereon.

63. In a phonograph, a tilttable record 95 rotating table, means for supporting a series of records above the same, means for actuating said table to discharge a record therefrom, and means actuated by said table for releasing a single record from said support. 100

64. In a phonograph, a rotating and tilttable table, means for depositing records thereon, means for discharging records therefrom, and operative connections between said tilttable table, record depositing 105 and record discharging means for setting them in operation by a tilting movement of said table.

65. In a phonograph, a normally counterbalanced tilttable record rotating table, 110 means for retaining the same in normal position when a record is thereon, coöperating reproducing mechanism and means controlled thereby and operated by gravity for successively tilting said table, returning the 115 same to normal position, and supplying a new record thereto.

66. In a phonograph, a rotating and tilttable table, a vertical member supported 120 above said table having a record support thereon, the lower end of said member extending down into an axial opening in a record on said table, a sound reproducing device for traversing a record thereon, and means for tilting said rotating table to lower 125 a record theron out of engagement with said vertical member and said sound reproducing device to allow the record to slide off of said table.

67. In a phonograph, record feeding 130

mechanism, a tiltable record rotating member, and means actuated by the latter upon completion of a record thereon to actuate said feeding mechanism to supply a new record thereto.

68. In a phonograph, record feeding mechanism, a movable record rotating and discharging member, and automatically actuating means for actuating said rotating member to discharge a record bodily therefrom and said feeding mechanism to supply a new record thereto.

69. In a phonograph, a record rotating table, a support disposed above the same, and feeding mechanism on said support including a guiding and actuating member extending substantially to the surface of said table.

70. In a phonograph, a record rotating and discharging table, reproducing mechanism coöperating with a record thereon, and means controlled by said mechanism for moving said table to discharge a record bodily therefrom after a predetermined rotation of said record.

71. In a phonograph, a record rotating and discharging member movable to discharge a record bodily therefrom, reproducing mechanism coöperating with a record thereon, and controlling mechanism for said member actuated when said reproducing mechanism reaches a predetermined point on said record.

72. In a phonograph, a record rotating and discharging member movable to discharge a record bodily therefrom, reproducing mechanism coöperating with a record thereon, and controlling mechanism for said member actuated when said reproducing mechanism reaches a fixed point irrespective of the length of the record.

73. In a phonograph, a record rotating member movable to discharge a record bodily therefrom, reproducing mechanism coöperating with a record thereon, and record discharging mechanism controlling said member and actuated when said reproducing mechanism reaches a predetermined point on said record.

74. In a phonograph, a record rotating member movable to discharge a record bodily therefrom, reproducing mechanism coöperating with a record thereon, and record discharging mechanism controlling said member and actuated when said reproducing mechanism reaches a fixed point irrespective of the length of the record.

75. In a phonograph, a record rotating and discharging member movable to discharge a record bodily therefrom, reproducing mechanism coöperating with a record thereon, and controlling mechanism for said member and said reproducing mechanism actuated when said reproducing mechanism

reaches a predetermined point on said record.

76. In a phonograph, a record rotating member movable to discharge a record bodily therefrom, reproducing mechanism coöperating with a record thereon, and controlling mechanism for said reproducing mechanism actuated when said reproducing mechanism reaches a fixed point irrespective of the length of the record.

77. In a phonograph, a tiltable record rotating member, reproducing mechanism coöperating with a record thereon, and controlling mechanism for said rotating member actuated when said reproducing mechanism reaches a predetermined point on said record.

78. In a phonograph, a tiltable record rotating member, reproducing mechanism coöperating with a record thereon, and controlling mechanism for said rotating member actuated when said reproducing mechanism reaches a fixed point irrespective of the length of the record.

79. In a phonograph, a tilting record rotating member, mechanism normally holding said member in operative position, reproducing mechanism, and means controlled by said reproducing mechanism for releasing said holding mechanism.

80. In a phonograph, a tilting record rotating member, mechanism normally holding said member in operative position, reproducing mechanism, and means controlled thereby for releasing said holding mechanism and moving said reproducing mechanism toward inoperative position.

81. In a phonograph, a rotating record table movable to and from operative position, mechanism for holding said table in operative position, movable reproducing mechanism, and means controlled thereby for releasing said holding mechanism.

82. In a phonograph, a rotating record table movable to and from operative position, mechanism for holding said table in operative position, movable reproducing mechanism, means controlled thereby for releasing said holding mechanism, and means for thereafter returning said table to operative position.

83. In a phonograph, a rotating record table movable to and from operative position, mechanism for holding said table in operative position, movable reproducing mechanism, means controlled thereby for releasing said holding mechanism, means for thereafter returning said table to operative position, and means for thereafter supplying a new record to said table.

84. In a phonograph, a rotating record table, mechanism for holding said table in operative position, movable reproducing mechanism, and coöperating means con-

trolled thereby for releasing said table to discharge a record therefrom, returning said table to operative position, supplying a new record thereto, and applying said reproducing means to said record.

85. In a phonograph, a record rotating member, reproducing mechanism for coöperating with a record thereon, and means operatively associated therewith for supporting and simultaneously gently lowering said reproducing mechanism into operative position upon the edge of a record on said record rotating member.

86. In a phonograph, a record rotating member, reproducing mechanism movable over a record thereon, and means operatively connectible with said record rotating member for gently lowering said reproducing mechanism into operative position upon the edge of a record on said record rotating member.

87. In a phonograph, a record rotating member, floating reproducing mechanism for coöperating with a record thereon, means for swinging said mechanism laterally to inoperative position, and means for thereafter elevating said mechanism and lowering the same gently into operative position upon the edge of a record on said record rotating member.

88. In a phonograph, a record rotating member, reproducing mechanism for coöperating with a record thereon, and means for lowering the latter into operative position upon a record including a rotatable lowering member the periphery of which supports and operatively engages a portion of said reproducing mechanism.

89. In a phonograph, reproducing mechanism, means for lowering the same into operative position upon a record including a rotatable lowering member the periphery of which supports and operatively engages a portion of said reproducing mechanism, and means actuated upon the completion of a record for bringing said reproducing mechanism into operative relation with said rotating member.

90. In a phonograph, a record rotating and discharging member, reproducing mechanism for coöperating with a record thereon, and means actuated by the movement of said record rotating member for lowering said reproducing mechanism into operative position upon a record including a rotatable

lowering member the periphery of which supports and operatively engages a portion of said reproducing mechanism.

91. In a phonograph, a rotating table, sound reproducing mechanism for traversing a record thereon, needle placing mechanism for said reproducing mechanism comprising a spiral gear, a wheel engaging said rotating table for driving said spiral gear, a wheel located below said sound reproducing mechanism operatively connected with said spiral gear, and means on said sound reproducing mechanism bearing on said wheel and riding over the same lifting said sound reproducing mechanism up over a record on said rotating table.

92. In a phonograph, a rotating and tiltable table, sound reproducing mechanism for traversing a record thereon, in combination with needle placing mechanism controlled by and tiltable with said table and comprising a spiral gear, a wheel engaging said rotating table for driving said spiral gear, a wheel located below said sound reproducing mechanism operatively connected with said spiral gear, and projections from said reproducing mechanism bearing on said wheel and riding up over said wheel and lifting said sound reproducer up over a record on said table.

93. In a phonograph, a rotating and tiltable table, a transverse rock shaft forming a support therefor, upright posts on each side of said rotating table, a record support carried on said posts and disposed centrally with said table, means carried on said support for supporting a series of records at their centers and delivering them separately therefrom, said centrally disposed member extending close to said rotating table, sound reproducing mechanism for traversing said records, means for placing the sound reproducing mechanism upon a record, means for discharging a record from said table, a receptacle, and suitable guides for directing the discharged records into said receptacle.

In witness whereof, I hereunto subscribe my name this 28th day of March, A. D., 1916.

CLEMMA R. RANEY.
